STRAP CONSTRUCTION FOR BATHING SANDALS

Burton P. Daugherty, Jr., Washington, D. C.

Application September 7, 1951, Serial No. 245,493

3 Claims. (Cl. 36—11.5)

1

This invention relates to an article of footwear, and more particularly, to a sandal having a novel construction including an improved means for securing the strap to the sole.

In the prior art sandals having straps for securing the sole to the foot of the wearer are well known. However, these prior art sandals have several defects or disadvantages. More specifically, the straps are frequently in the form of cord, thongs, or other narrow strips which tend to cut and chafe the foot. In those devices which have employed broad straps the latter tended to twist and thereby made it difficult to place the sandal on the foot, as well as being irritating and uncomfortable to wear. Furthermore, the prior art sandals have securing means for connecting the straps to the sole which are unreliable in that they frequently tend to break, provide unsightly and bothersome projecting connections, and are relatively expensive as to cost of manufacture.

It is, therefore, a primary object of the present invention to provide a sandal having broad straps so arranged that the straps will lie flat against the foot of the wearer throughout their lengths and will be restrained against twisting out of this position, thereby preventing any chafing or cutting.

Another object of the present invention is to provide a novel securing means for the straps, these securing means comprising strap portions extending downwardly through apertures in the sole and having enlarged shoulders abutting against the lower surface of the sole so as to restrain the strap portions against upward movement.

A further object is to provide hollow rubber bosses on the lower surface of the sole for enclosing said shoulder projections, the bosses serving both as a protective enclosure for the enlarged shoulders and also as a suction cup gripping means to improve the traction of the sole with respect to the ground.

Other objects and advantages of the present invention will be apparent and are inherent in the structure as described in the specification and as shown in the drawing wherein:

Figure 1 is a top plan view of a sandal constructed in accordance with the present invention,

Figure 2 is a bottom plan view showing the lower surface of the sole,

Figure 3 is a vertical section taken substantially on the line 3—3 of Figure 1, and shows the structural details of a rubber boss and the enclosed shoulder therein for restraining the for-

2

ward ends of the strap sections against upward movement; and

Figure 4 is a transverse vertical sectional view taken substantially on the line 4—4 of Figure 1 and shows the rubber boss and securing means for the rear ends of the strap sections.

Referring to the drawing, the reference numeral 11 indicates generally the sole of the sandal. The upper surface 12 of the sole 11 is preferably provided with a series of longitudinal slits 13 crossed by transverse slits 14 which are spaced relatively closer than, and are somewhat shallower than, the longitudinal slits 13. At the forward or toe end 15 and at the rear or heel end 16 of the sole 11 are provided longitudinally extending slits 17 and 18 respectively, the slits 17 and 18 being relatively closer to each other and shallow, similar to the transverse slits 14.

Referring now to Figure 2, the lower surface 19 of the sole 11 is preferably provided with a peripherally extending rib or raised portion 20. Within the area enclosed by the rib 20 are several different types of projecting configurations such as at 21, 22, 23, 24 and 25, these projections serving as a gripping means to increase the traction of the sole with respect to the ground and also providing a decorative effect. It will be obvious that the particular shapes of these configurations have no bearing on the present invention and may be varied as desired.

The strap member, generally designated as 26, comprises two strap sections 27 and 28. Each of the strap sections 27 and 28 extends from its rear end 27'—28' forwardly to its respective forward end 27''—28''. The strap member 26 is preferably made integral so that the strap section forward end 27'' is continuous with the strap section forward end 28''. However, if desired, the strap sections 27 and 28 may be made of individual pieces and secured together at their forward ends 27''—28''. It will be noted that the strap sections 27 and 28 are of a somewhat arcuate configuration so as to accommodate the contour of the wearer's foot.

Approximately adjacent the forward or toe end 15 of the lower surface of the sole 11 and intermediate the longitudinal side edges 29 and 30 of the latter there is provided a downwardly extending hollow boss or projection 31. The boss 31 is preferably of a circular configuration as shown in the drawing, but it will be obvious that other cross sectional shapes may be employed.

Referring now to Figure 3, the sole 11 is provided with an aperture 32 coaxial and communicating with the opening in the boss 31. A pro-

jection 33 extends downwardly through the aperture 32 and is provided at its lower end with an enlarged shoulder portion 34 which abuts against the lower surface of the sole 11. The upper end of the projection 33 is adhesively or otherwise secured to the forward ends 27''-28'' of the strap sections 27 and 28. It will also be noted that the lower portion of the boss 31 extends downwardly beneath the enlarged shoulder 34 so as to provide a hollow space 35 within the boss 31. This enables the boss 31 to act as a suction cup gripping means as will be explained in more detail below.

A pair of bosses 36 and 37 are provided approximately adjacent the rear or heel end 16 of the sole 11 and extend downwardly from the peripheral rib 20 with which they are integrally formed.

As best seen in Figure 1, the bosses 36 and 37 are constructed similarly to the boss 31 described above. The sole 11 is provided with a pair of apertures 38 extending therethrough, each aperture 38 being coaxial and communicating with a respective one of the openings in the interior of the bosses 36 and 37. Each of the rear ends 27'-28' of the strap sections 27 and 28 is provided with a reduced portion 39 extending downwardly through a respective aperture 38. The portions 39 are each provided with an enlarged shoulder 40 abutting against the lower surface of the sole 11 so as to restrain the strap section ends 27'-28' against upward movement. The shoulders 40 are enclosed by the bosses 36 and 37 but fill only the upper portion of the space within the bosses 36 and 37 so as to provide an air space 41 within the lower portions of each of the bosses 36 and 37. The air space 41 enable the bosses 36 and 37 to act as a suction cup or gripping means so as to increase the traction of the sole with respect to the ground.

Referring now to Figure 1, it will be noted that the strap sections 27 and 28 are of greater width than thickness so as to provide large flat surface areas adapted to contact the foot of the wearer without causing chafing or irritation. The rear ends 27'-28' of the strap sections 27 and 28 lie substantially horizontal and flat against the upper surface 12 of the sole 11. As the strap sections 27 and 28 extend outwardly and forwardly they twist gradually so that their intermediate portions 27'''-28''' are approximately vertical. The strap sections 27 and 28 continue to twist as they extend forwardly until at the forward ends 27''-28'' the strap sections 27 and 28 have each twisted approximately 180° so as to lie substantially horizontal and in inverted relation with respect to their original alignment at the rear ends 27'-28'. This arrangement of the strap sections 27 and 28 provides that their broad interior surfaces lie flat against the surface of the wearer's foot. Furthermore, although the strap sections 27 and 28 and also their projecting reduced portions 33-39 are preferably made of rubber and are, therefore, somewhat resilient, these elements are sufficiently stiff so that the strap sections 27 and 28 tend to maintain their open arcuate raised positions shown in the drawing so as to enable the wearer to slip his foot between and beneath the strap sections 27 and 28 with ease and rapidity.

As shown in Figure 1 the projecting or reduced portion 33 to which the strap section forward ends 27''-28'' are secured is relatively narrow in the transverse direction so as to easily fit between the large and second toes of the wearer.

The sole 11 and strap sections 27 and 28 may

be made of any suitable material such as rubber, plastic, fabric or the like. However, rubber is thought preferable in that it is easily washable, durable, and soft and comfortable to the wearer. Furthermore, the resilient nature of rubber tends to urge or bias the strap sections 27 and 28 toward the open arcuate raised position shown in the drawing whereby the shoulder portions 34 and 40 are maintained in abutment against the sole 11 and the wearer may slip his foot quickly and easily beneath and between the strap sections 27 and 28.

As a result of the resilient nature of the rubber material of the strap sections 27 and 28, the shoulder portions 34 and 40 are maintained in the upper portions of the bosses 31 and 36 whereby the free air spaces 35 and 41 in the lower portions of the bosses 31 and 36 allow the latter to act as suction cups which increase the gripping or traction effect of the sole 11 with respect to the ground.

It is to be understood that the specific embodiment of the invention shown in the drawing and described in the specification is merely illustrative of one of the many forms which the invention may take in practice; the scope of the invention being delineated in the appended claims.

What I claim is:

1. A sandal comprising a sole having an upper surface upon which the foot of the wearer may rest and a lower surface adapted to contact the ground, a strap member extending above said sole and being adapted to extend over the foot of the wearer for holding the sandal in wearing position on the foot, said strap member being of greater width than thickness and comprising two sections each having a rear end located approximately adjacent the rear or heel end of the sole and a forward end approximately adjacent the front or toe end of the sole, and a projection extending upwardly from the sole and secured at its upper end to one face of said strap section forward ends, said strap sections lying substantially horizontal at their connection to said projection and gradually twisting 180° inwardly as they extend rearwardly so as to be substantially horizontal and inverted at their rear ends whereby the entire length of the strap sections will lie substantially flat against the surface of the wearer's foot, and connections between said sole and the rear ends of said strap sections on the opposite face of said strap sections.

2. A sandal comprising a sole having an upper surface upon which the foot of the wearer may rest and a lower surface adapted to contact the ground, a strap member extending above said sole and being adapted to extend over the foot of the wearer for holding the sandal in wearing position on the foot, said strap member being of greater width than the thickness and comprising two sections each having a rear end located approximately adjacent the rear or heel end of the sole and a forward end approximately adjacent the front or toe end of the sole, a projection extending upwardly from the sole and secured at its upper end to one face of said strap section forward ends, said strap sections lying substantially horizontal at their forward ends and gradually twisting 180° inwardly as they extend rearwardly so as to be substantially horizontal and inverted at their rear ends whereby the entire length of the strap sections will lie substantially flat against the surface of the wearer's foot, said sole having three apertures therethrough, said projection and said strap section rear ends each

having a portion extending downwardly through a respective one of said apertures, the portions on said rear ends being on the opposite face of said strap sections and an enlarged shoulder on each of the lowermost ends of said portions and abutting against said sole lower surface so as to retain said strap sections in twisted relation and said strap section ends against upward movement with respect to the sole.

3. A sandal comprising a sole having an upper surface upon which the foot of the wearer may rest and a lower surface adapted to contact the ground, a strap member extending above said sole and being adapted to extend over the foot of the wearer for holding the sandal in 10 wearing position on the foot, said strap member being of greater width than the thickness and comprising two sections each having a rear end located approximately adjacent the rear or heel end of the sole and a forward end approximately adjacent the front or toe end of the sole, a projection extending upwardly from the sole and secured at its upper end to one face of said strap section forward ends, said strap sections lying substantially horizontal at their forward ends and gradually twisting 180° inwardly as they extend rearwardly so as to be substantially horizontal and inverted at their rear ends whereby the entire length of the strap sections will lie substantially flat against the surface of the 30 wearer's foot, said sole having three apertures therethrough, said projection and said strap sec-

tion rear ends each having a portion extending downwardly through a respective one of said apertures, the portions on said rear ends being on the opposite face of said strap sections, an enlarged shoulder on each of the lowermost ends of said portions and abutting against said sole lower surface so as to retain said strap sections in twisted relation and said strap section ends against upward movement with respect to the sole, and three hollow rubber bosses secured to the lower surface of the sole, each boss surrounding a respective one of said enlarged shoulders and extending downwardly thereabout and downwardly therebelow.
